DESIGN FOR A GARMENT DRYING APPARATUS

Fernand E. Beluche, Williamsville, and William F. Brace, Buffalo, N. Y.

Application June 21, 1938, Serial No. 77,969

Term of patent 14 years

To all whom it may concern:

Be it known, that we, Fernand E. Beluche and William F. Brace, both citizens of the United States and residing respectively at Williamsville and Buffalo, in the county of Erie and State of New York, have invented a new, original, and ornamental Design for a Garment Drying Apparatus, of which the following is a specification, reference being had to the accompanying drawing, forming part thereof.

Fig. 1 is a perspective view of the garment drying apparatus embodying our new design viewed from the front thereof.

Fig. 2 is a similar view of the same viewed from the rear thereof.

We claim:

The ornamental design for a garment drying apparatus, as shown.

FERNAND E. BELUCHE.
WILLIAM F. BRACE.
